Primary Examiner—James M. Gandy*Assistant Examiner*—Marcus Jackson*Attorney, Agent, or Firm*—J. Addison Mathews[57] **CLAIM**

The ornamental design for a smoke detector housing, as shown and described.

DESCRIPTION

FIG. 1 is a front elevational view of a smoke detector housing showing my new design;

FIG. 2 is a top plan view thereof rotated one hundred and eighty degrees compared to FIG. 1;

FIG. 3 is a rear elevational view thereof.

FIG. 4 is a right side elevational view thereof, with the opposite side being a mirror image; and,

FIG. 5 is a bottom plan view thereof.

FIG. 1

FIG. 2

FIG. 3

FIG. 4

FIG. 5
